UNITED STATES PATENT OFFICE.

CHARLES ARTHUR POWELL, OF RACINE, WISCONSIN.

DESIGN FOR AN IRONING-BOARD.

SPECIFICATION forming part of Design No. 31,719, dated October 24, 1899.

Application filed August 12, 1899. Serial No. 727,074. Term of patent 7 years.

To all whom it may concern:

Be it known that I, CHARLES ARTHUR POWELL, a citizen of the United States, residing at Racine, in the county of Racine and State of Wisconsin, have invented certain new and useful Improvements in a Design for Ironing-Boards; and I do declare the following to be a full, clear, and exact description of the invention, such as will enable others skilled in the art to which it appertains to make and use the same, reference being had to the accompanying drawing, and to the figures of reference marked thereon, which forms a part of this specification.

My invention relates to a design for ironing-boards; and it consists in the contour and form of board hereinafter described.

The accompanying drawing illustrates in perspective an ironing-board embodying my design.

The body 1 of the board is of substantially oval form, with a narrowed lateral extension 2, having its end 3 rounded, as shown. The greatest length of the body portion 1 is in the direction of the length of the extension 2, or, in other words, the board is extended at one

of the ends or points of the oval to form the part 2 and not from the side of the oval. The sides 4 of the body portion of the board curve gradually at their point of juncture with the extension 2, giving a graceful appearance to the article.

Depending from the under side of the body 1 is a clamp 5, having a depending extension 6, formed with rounded corners 7. The flange 8 of the clamp is curved or rounded at the points 9 to impart a finished and attractive appearance thereto.

The essential feature of the design is the oval-shaped body portion with the extension 2 projecting from one end of the oval, the depending clamp constituting a minor feature of the design.

I claim—

The design for an ironing-board shown and described.

In testimony whereof I affix my signature in presence of two witnesses.

CHARLES ARTHUR POWELL.
